FURNACE CONTROL MECHANISM

Christian S. Andersen, Warren, Pa., assignor to
Pennsylvania Furnace & Iron Co., Warren, Pa.,
a corporation of Pennsylvania

Application September 10, 1937, Serial No. 163,167

2 Claims. (Cl. 236—21)

This invention relates to improvements in furnace control mechanism and more particularly to a novel control mechanism for a boiler furnace whereby a control member is actuated in response to a steam pressure condition or a water level condition.

One of the features of my invention is the provision of a novel control valve and operating mechanism therefor wherein the same valve may be operated either in response to a steam pressure condition or to a water level condition.

Another feature of my invention is the arrangement of a novel toggle actuated snap action control member and automatic means for actuating the control member in response to a boiler condition.

My invention also includes a novel actuating device for a control member operable in response to a boiler water level condition. This novel device also includes a novel arrangement of a control member operating lever extending from within a float chamber to a point outside the same and novel sealing means for the opening through which the operating lever passes.

Other features of my invention will appear from the accompanying drawings and specifications and the essential feature thereof will be summarized in the claims.

In the drawings,

Fig. 1 is a sectional view through a water leg of a boiler equipped with my novel control mechanism and taken along the line 1—1 of Fig. 2;

Fig. 2 is an elevational view of the mechanism of Fig. 1 taken from the right-hand side thereof;

Figs. 3, 4 and 5 are enlarged detail sections of a portion of the mechanism of Fig. 1, showing the parts in various operated positions; while

Fig. 6 is a view similar to Fig. 5, showing a modified form of the valve actuating plungers.

My invention is applicable to a boiler furnace having control mechanism which it is desired to operate automatically in response to steam pressure or water level conditions. I have illustrated at 10 the water leg or float chamber of such a boiler wherein it will be understood that chamber 10 is partially filled with water, the upper portions being filled with steam at boiler pressure as is usual in such cases. For illustrative purposes only I have indicated at 11 a portion of a furnace control mechanism for operation in response to a steam pressure or water level condition in the boiler. The member illustrated is a diaphragm operated gas valve which, for instance, might supply gas to the heat generating burner of the boiler furnace. This valve has a

port 11a which is closed or opened in response to the pressure conditions on opposite sides of the diaphragm 11b. This diaphragm has a small vent 11c leading into the chamber 12 above the diaphragm. This chamber is vented as at 13 and when gas pressure is exerted below the diaphragm 11b and chamber 12 is vented to atmosphere, the diaphragm will hold the port 11a open as indicated in Fig. 1. However, if in response to a boiler condition it is desired to shut off the fuel to the burner, gas or other fluid pressure may be admitted through conduit 14 to chamber 12 to create in that chamber equal or greater pressure than that existing below the diaphragm, with the result that port 11a is closed and the burner 15 ceases to generate heat.

For the control of such a valve 11 or other control member having similar control effects, I have provided a valve 15 having a port 15a and a valve plunger 15b reciprocable to open or close the port 15a whereby gas, for instance, supplied at 16 may pass to conduit 14 and chamber 12 when valve 15b is in open position. A spring 17 biases the valve toward closed position and plungers 18 and 19 may be automatically actuated, as will presently appear, by a boiler condition to open the valve 15b and dump gas pressure into chamber 12. A flexible diaphragm 20 seals the valve against gas leakage to atmosphere.

Means is provided for actuating valve 15 in response to a predetermined steam pressure condition in the boiler. In the form shown a metal bellows 21 subjected to steam pressure in the water leg is connected with an actuating stem 22 extending upwardly out of the water leg casing. This connection is sealed against steam leakage at 23. Lever 24 pivoted on the casing at 25 is in operative engagement at the one end with the pin 22 and at the other end with rod 26, which extends downwardly and is provided at its lower end with the adjustable abutment 27. A bellcrank operating arm 28 is pivotally mounted on the framework at 29 and has a leg 28a engaging the abutment 27 and an upwardly extending yoke 28b carrying a plunger 30 which engages in a notch 31a of rocker 31 which in turn is pivotally mounted on the frame at 32. The free end 31b of the rocker engages the notched portion 18a of the valve operating plunger 18. The plunger 30 has a downwardly extending pin 30a reciprocably mounted in the yoke 28b and spring pressed upwardly by the spring 33 which is compressed between the shoulder 28c of yoke 28b and the lower side faces of the plunger head 30. In effect the rocker 31 and the plunger 30 form a snap acting

toggle which in the normal position of the parts lies with the rocker in the position of Fig. 5 but in the actuated position snaps the rocker to the position of Fig. 3, thus opening valve 15.

Means is provided for adjusting the action of the mechanism just described in response to the pressure exerted on the bellows 21. To this end a yoke 34 on lever 24 is provided with a downwardly extending pin 34a and about the pin is 10 a helical spring 35 compressed between the stop pin 34b and an adjustable cap 36 which has threaded engagement with a portion of the fixed casing. The tendency of increased pressure in bellows 21 is to cause a clockwise movement of lever 24 about the pivot 25. By adjusting the 15 compression of spring 35 by means of the cap 36 this action may be adjusted and modified so as to set the device to act at a predetermined steam pressure.

20 The operation of the portion of the control mechanism just described will be readily understood. Upon the pressure in bellows 21 reaching a predetermined point, pin 22 moves upwardly, causing clockwise movement of lever 24, downward movement of rod 26 and clockwise movement of the bellcrank member 28. This causes movement toward the right of yoke 28b and moves the toggle 30, 31 toward center position, that is, with plunger 30 in line between pivots 32 and 29. 25 This compresses spring 33, and if the movement of yoke 28b toward the right continues until the plunger 30 passes the center line position, spring 33 is effective to snap the rocker 31 to the position of Fig. 3, moving plungers 18 and 19 inwardly and 30 opening valve 15. This will dump gas pressure on top of diaphragm 11b and shut off gas supply to the boiler burner.

35 The means for actuating valve 15 in response to a water level condition comprises a float 38 in the chamber 10, this float having a downwardly extending guide part 38a and an upwardly extending pin 38b by which it is connected to the control mechanism. This pin is pivotally connected at 39 with the lever 40 which in turn is mounted on the 40 pivot 41 which is rigid with the casing 10. The lever 40 in reality forms one arm of a bellcrank arrangement, the other arm of which is the upwardly extending member 42 engaging the valve actuating plunger 19.

45 I provide a novel structure at the point where the lever 40 passes outside of the casing 10. A flexible bellows 43 is sealed to the lever 40 at the end 43a and is sealed to the cap 44 at the end of the bellows 43b. The cap 44 is tightly secured to the cover plate 45 which in turn is secured in 50 sealed relationship with the flanged opening 46 through which this mechanism is inserted in the casing 10. The member 47 is a supporting ring for the lever 40 and connected mechanism. It 55 results from this structure that the lever 40 may have a tilting action about the pivot 41 while remaining sealed to the casing 10 without danger of steam or water leakage. At the same time, variations in temperature or pressure within the 60 casing 10 have no effect on lever 40 because of the fixed pivot 41. In other words, the temperature and pressure effective on rod 40 and bellows 43 will cause no movement of the arm 42.

The operation of the low water control just described is as follows: Upon the water level in the float chamber 10 dropping to a predetermined low point, float 38 will move downwardly, causing a downward movement of lever 40 and a counter-clockwise movement of the arm 42 about the pin 41. This moves the valve actuating plunger 19 inwardly as shown in Fig. 4, thus opening valve 15 and dumping gas pressure on top of diaphragm 11b, closing off the supply of gas to the boiler 10 burner.

5 A modification of the valve actuating plungers is shown in Fig. 6, wherein the head 19a of plunger 19 has been omitted and this plunger is given the form shown at 48. In the form shown 15 in Figs. 1 to 5, when plunger 18 is actuated to the position shown in Fig. 3 it carries plunger 19 with it. This moves the plunger away from arm 42, which ordinarily is not objectionable but with the plunger formed as is shown at 48 the plunger 18 20 may be moved independently of the plunger 48.

25 It will be noted that the valve 15 is actuated either in response to a predetermined steam pressure or in response to a predetermined water level or in response to both conditions.

30 While I have shown the valve 15a open for the purpose of producing a stated control effect on valve 11, it will be understood that I intend my novel control mechanism for use with any suitable control member wherein the action of a member 35 placed at the position 15 will cause the desired control effect with respect to the boiler control mechanism. In other words, I have shown mechanism automatically responsive to a variation in steam pressure and water level conditions 35 by which any desired control action may be brought about.

What I claim is:

1. In control mechanism of the class described 40 for a boiler having a water level responsive device and having a steam pressure responsive device, the combination of a member for controlling fuel input to said boiler, two actuators for said control member including a sleeve surrounding a rod, said rod being reciprocable relative to said sleeve to 45 actuate said control member independently of sleeve motion, and operative connections between one of said devices and said rod and between the other of said devices and said sleeve.

2. In boiler control mechanism of the class 50 described, the combination of a device responsive to a condition in said boiler, a member for controlling fuel input to said boiler, an actuator for said control member, and an operative connection between said device and said control member comprising a lever having an end oscillatable in the general direction of actuator movement, a spring-pressed plunger on the end of said lever and reciprocable endwise of said lever, a rocker lever having a fixed pivot intermediate its ends, one end of 55 said rocker lever operatively engaging said first named lever and the other end of said rocker lever operatively engaging said actuator, whereby said plunger and said rocker lever form a yieldable toggle adapted to snap to either side of dead center 60 to hold said actuator in inoperative and actuated positions.

CHRISTIAN S. ANDERSEN.
